UNITED STATES PATENT OFFICE

2,048,805

CORSET FASTENER

Robert McAuley, Chalk River, Ontario, Canada

Application August 27, 1934, Serial No. 741,673

2 Claims. (Cl. 24—205)

This invention relates to new and useful improvements in a corset fastener. The primary object of the invention being to provide a fastener that may be instantaneously released in case of emergency.

A further object of the invention is to provide movable fastening means on one side of the said corset arranged to engage fixed members on the opposite side thereof the said movable fastening means being actuated simultaneously to engage or release the said fixed members.

A still further object of the invention is to provide a corset fastener as described having means attached thereto whereby to retain the device in the fastened position and prevent it being inadvertently released.

With these and other objects in view that may appear while the description proceeds the invention consists in the novel construction and arrangement of parts as hereinafter more specifically set forth, claimed and shown in the accompanying drawing forming a part of this specification and in which:—

Fig. 1 is a front view of my improved fastener in the closed position.

Fig. 2 is a similar view showing the fasteners released.

Fig. 3 is an enlarged detail view of the lower end thereof showing the retaining means thereon.

Fig. 4 is an enlarged detail view of an alternative construction of the retaining means.

Referring more in detail to the drawing in which similar reference characters designate corresponding parts throughout the several views it will be seen the invention comprises an inner longitudinal member 10, having a plurality of downwardly curved projections 11 formed integral therewith and constituting the upper halves of the fastening elements. An outer longitudinal member 12 of similar construction is slidably mounted on the member 10 by means of pins 13 having enlarged heads to retain the same thereon. Elongated orifices 14 are provided therein to engage the said pins thereby permitting the member 12 to move in order to bring the projections 11 and the corresponding projections 15 on the member 12 into contacting relation to each other. The said projections 11 and 15 are slightly bent outwards and inwards respectively so that the outer extremities thereof shall meet.

On the opposite side of the corset is another longitudinal member 16 on which a plurality of studs 17 are secured, the said studs being arranged in position on the said member to correspond with the aforesaid fastening elements.

It will be seen that when the member 12 is pushed upwards the projections will engage each other around the studs 17 and securely hold the corset fastened. Should the occasion arise for an emergency unfastening the member 12 is pulled downward and the fasteners will all release their grip on the studs and the corset will be thereby unfastened.

A hinged fastener 18 is provided on the lower end of the longitudinal member 12 and is positioned to engage a slot 19 in the member 16 thereby providing means closing the lower end of the corset and at the same time retaining the fastening elements closed upon the studs and thus preventing the same becoming inadvertently unfastened by the movement of the member 12.

In Fig. 4 is shown an alternate fastener for the lower end of the corset which comprises a spring steel member 20 having a slot 21 cut therein. Said slot terminates in a slightly enlarged circular orifice 22. On the member 16 is a stud 23 similar to the studs 17 onto which the spring fastener 20 is pressed. Owing to the spring action of the fastener the stud may be readily engaged or disengaged from the slot. The said fastener and stud are positioned to be engaged when the members 11 and 15 are closed on the studs and thus prevent a downward movement of the member 12 until the said fastener is released.

It is believed that the construction and advantages of the structure shown will be apparent from the foregoing paragraphs taken in conjunction with the accompanying drawing without further detailed description.

While the preferred embodiment of the invention has been disclosed it is understood that minor changes in the details of construction, combination and arrangement of co-operating elements may be resorted to within the scope of what is claimed without departing from the spirit of the invention.

I claim:—

1. In a corset fastener, the combination of a flat strip having a series of laterally extending projections formed integral with one longitudinal edge, a relatively movable strip slidably mounted on said first mentioned strip having also a series of lateral projections formed integral with one longitudinal edge, the projections of said strips having their ends curved towards each other to form co-acting hooks, said hooks being off-set to lie in the same plane, so as to contact with each other upon movement of said movable strip in one direction, and a strip having headed pins around which said projections engage. 55

2. In a corset fastener, the combination of a flat strip having along one of its longitudinal edges a series of spaced laterally extending integral projections, a relatively movable strip slidably mounted on said first mentioned strip having also a series of lateral projections formed integral with one longitudinal edge, the projections of said strips having their ends curved towards each other to form co-acting hooks, said hooks

being off-set to lie in the same plane, so as to contact with each other upon movement of said movable strip in one direction, a strip having headed pins adapted to be gripped by said projections and a fastening element for securing said movable strip and said last mentioned strip together when said projections are engaged with said pins. 5

ROBERT McAULEY.
